UNITED STATES PATENT OFFICE.

WILLIAM A. JOHNSTON, OF HOMER, LOUISIANA.

DESIGN FOR A CLASP.

SPECIFICATION forming part of Design No. 26,708, dated March 2, 1897.

Application filed January 19, 1897. Serial No. 619,815. Term of patent 7 years.

To all whom it may concern:

Be it known that I, WILLIAM A. JOHNSTON, a citizen of the United States, residing at Homer, in the parish of Claiborne and State 5 of Louisiana, have invented a new and original Design for a Clasp, of which the following is a specification.

This invention relates to a new and original design for a clasp; and it has for its object to 10 provide a design of this character that shall be both useful and ornamental.

The leading feature of the design resides in a flat oblong body having at one side a pair 15 of opposite flat rectangular figures extended from and disposed at right angles to the side edges of the body, said body being extended at one end beyond the plane of said rectangular figures and formed at opposite side edges of such extended end with right-angled 20 rounded projections and a flat acorn-shaped figure lying between such projections in a plane adjacent to and parallel with one side of the body, said flat acorn-shaped figure having opposite convexed side edges converging 25 to a point and a wide base portion having rounded ends meeting said side edges.

In the drawings, Figure 1 is a perspective view of a clasp embodying the herein-described design. Fig. 2 is a plan view thereof. 30 Fig. 3 is a perspective view of the reverse side of the clasp.

Referring to the accompanying drawings, the numeral 1 designates a flat oblong body having extended at right angles therefrom at

opposite side edges a pair of opposite flat rectangular figures 2, formed in their edges lying parallel with the body with a regular series of convexed scallops 3. The body 1 is extended at one end beyond the plane of the figures 2, and is formed at opposite side edges 4 of such extended end with right-angled rounded projections 4, between which is arranged a flat acorn-shaped figure 5. The figure 5 lies in a plane adjacent to and parallel with the body 1, and is formed with opposite 45 convexed side edges 6, converging to a point, and a wide base portion having rounded ends 7 meeting said edges 6. The figure 5 is formed near its point or vertex at opposite points with pointed projections 8, touching the body 1, 50 and at its end opposite the point or vertex with an offstanding rounded ear 9. The wide base portion of the figure 5 has its surface covered with hatch-lines 10, and surface lines 11 converge from the base portion toward the 55 vertex and extend in planes parallel with the side edges 6.

What I claim is—

The design for a clasp herein shown and described. 60

In testimony that I claim the foregoing as my own I have hereto affixed my signature in the presence of two witnesses.

WILLIAM A. JOHNSTON.

Witnesses:

JOHN H. SIGGERS,
WM. B. HUDSON.
